UNITED STATES PATENT OFFICE.

THORWALD THORSON, OF FOREST CITY, AND FRED M. ELLER, OF AMES, IOWA.

MORTAR-JOINT RAKER AND FINISHER.

1,310,639.

Specification of Letters Patent. Patented July 22, 1919.

Application filed January 7, 1919. Serial No. 269,993.

To all whom it may concern:

Be it known that we, THORWALD THORSON and FRED M. ELLER, citizens of the United States, residing, respectively, at Forest City 5 and Ames, in the counties of Winnebago and Story, State of Iowa, have invented a new and useful Mortar-Joint Raker and Finisher, of which the following is a specification.

- 10 It is the object of this invention to provide a simple tool adapted to be used for finishing mortar joints, the tool being adapted to be operated either by a push or by a pull.
- 15 It is within the province of the disclosure to improve generally and to enhance devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:—

- 30 Figure 1 shows in elevation, a tool constructed in accordance with the invention; Fig. 2 is an elevation wherein the tool is viewed at right angles to the showing of Fig. 1; and Figs. 3, 4, 5, 6 and 7 are elevations showing the various applications of the tool.

The device forming the subject matter of this application preferably is made of metal throughout and includes a handle 1 in the 40 form of a strip, having oppositely inclined ends 2 and 3 provided with grooves 4 receiving ribs 5 on bits 6 and 7, bit 6 being assembled with the end 3, and the bit 7 being assembled with the end 2. The bits 6 and 7 45 are held in place by screws 8 or in any other suitable way. As shown, the bit 7 is somewhat wider than the bit 6. The ends 9 of the bits 6 and 7 converge toward the ends of the handle 1 to form inner cutting edges 10 and outer cutting edges 11, extremities of the

parts 2 and 3 of the handle being beveled off flush with the outer inclined ends of the bits, as indicated at 25. The longitudinal or working edges of the bits are convexed as shown at 12. It will be understood that, so far as cross section is concerned, the working edges of the bits may be shaped in various ways, depending upon the shape which it is desired to impart to the mortar groove. This detail, however, is a mere matter of 55 design and need not be shown or described. The handle 1 is provided with openings 14 located near to the inner cutting edges 10, the handle being beveled along the edges of the openings 14, as indicated at 26, to correspond with the adjacent inclined end 9 of the bits 6 and 7.

As shown at 3, either of the bits may be pushed along a mortar groove, to raise the material, the tool operating as a plow. If 70 desired, the tool may be operated by a pull, as shown in Fig. 4, whereupon the inner cutting edge 10 will be effective, the mortar riding outwardly through the opening 14. As shown in Fig. 5, the tool may be 75 pushed or pulled, the convexed edge 12 of the bit serving to smooth down the bottom of the mortar groove. In Fig. 6, the tool is shown as being pulled backwardly in a mortar groove, whereupon the outer cutting 80 edge 11 will deepen the groove, as shown at 15. Fig. 7 discloses the fact that the outer cutting edge 11 of the bit may work closely into an angle as shown at 16.

Since the bits are tongue and grooved to 85 the ends of the handle 1, each bit may be held in place by a single securing element such as the screw 8. The bits 6 and 7 may be removed at any time, and be replaced by others of like or similar construction. 90

Having thus described the invention, what is claimed is:—

1. A tool of the class described comprising a handle, and a bit carried by one end of the handle, the ends of the bit converging 95 toward the handle to define inner and outer cutting edges, the handle having an opening located adjacent to the inner cutting edge.

2. A tool of the class described, comprising a handle and a bit carried by the end of 100

the handle, the end of the bit converging toward the handle to define inner and outer cutting edges, the handle having an opening located adjacent to the inner cutting edge, 5 the longitudinal edge of the bit being convexed.

In testimony that we claim the foregoing

as our own, we have hereto affixed our signatures in the presence of two witnesses.

THORWALD THORSON.
FRED M. ELLER.
